(74) *Attorney, Agent, or Firm* — Kolitch Romano Dascenzo Gates LLC(57) **CLAIM**

The ornamental design for goggles, as shown and described.

DESCRIPTION

FIG. 1 is a front perspective view of goggles, showing the new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

(Continued)

The broken lines shown in the drawings illustrate portions of the goggles that form no part of the claimed design. The dot-dash broken lines define the bounds of the claimed design and form no part thereof.

1 Claim, 8 Drawing Sheets
